UNITED STATES PATENT OFFICE.

WILLIAM NOLL, OF CHICAGO, ILLINOIS, ASSIGNOR TO NOLL ALUMINUM HEEL CO., A COPARTNERSHIP CONSISTING OF VERNON F. BLOOM, WILLIAM NOLL, AND JOHN NOLL, OF CHICAGO, ILLINOIS.

METAL HEEL.

Application filed September 25, 1919. Serial No. 326,186.

To all whom it may concern:

Be it known that I, WILLIAM NOLL, a citizen of the United States, and a resident of the city of Chicago, county of Cook, and 5 State of Illinois, have invented certain new and useful Improvements in Metal Heels, of which the following is a specification.

My invention relates to new and useful improvements in metal heels, and has for its 10 object the provision of a novel means of securing a metal heel to the shoe.

Other objects will appear hereinafter.

The invention consists in the combinations and arrangements of parts hereinafter described and claimed.

The invention will be best understood by reference to the accompanying drawings forming a part of this specification, and in which,

20 Fig. 1 is a longitudinal vertical sectional view of my invention.

Fig. 2 is a transverse vertical sectional view of my invention.

25 Fig. 3 is a bottom plan view of the plate used in my invention.

Fig. 4 is a top plan view of my invention.

The approved form of construction comprises a metal heel portion 5, formed in the usual shape of a high heel, which is used on 30 women's shoes. Adapted to seat in the upper end of the member 5, so that the edge thereof will lie flush, with the upper edge of the member 5, is a plate 6. Projecting upwardly from the member 6, are pointed members 7, which are adapted to project into the shoe 7' and secure the member 6 temporarily thereto. Formed in the member 6, extending 35 around the edge thereof, are perforations 8, by means of which the member 6 may be fastened permanently to the shoe by the use of tacks or nails.

Projecting downwardly from the member 6, is an interiorly threaded socket 9, in which is adapted to engage a threaded member 10, which projects through an opening 11, formed in a nonmetallic member 14, which is insertable in the lower end of the member 5. An enlarged opening 12 is provided in the member 14, for the reception of the enlarged head 13, of the member 10. As clearly seen in Fig. 1 and Fig. 2, the member 14 is tapered, the lower end being the larger.

In attaching the heel to the shoe 7', the plate 6, is positioned upon the shoe and the shell 5, is then positioned over the member 6, so that the two members are loosely arranged in assembled position. The desired position of the heel upon the shoe is determined and the members 5 and 6, in their 60 loosely assembled position, are shifted accordingly. A blow is then delivered upon the lower or smaller end of the member 5, which drives the members 7 into the leather of the shoe 7'. The shell 5, is then lifted 65 from the member 6, whereupon the same may be permanently attached to the shoe, the member 7 preventing any shifting of the member 6, relatively to the shoe 7', after the shell 5 is removed. When the member 6 is permanently attached to the shoe, the member 5 is again assembled in its position upon the member 6, and the member 14 inserted in the lower end of the member 5. Upon threading the member 10 into the 70 socket 9, the members 6 and 14 are drawn into closer relation to each other, with the consequent result that the heel portion 5, is rigidly mounted in position. Secured to the heel plate 6, which is preferably made of 75 metal, and extending transversely thereof from the socket member 9, and preferably made integral with the member 6, are reinforcing walls 15. Similarly constructed reinforcing walls 16, extend longitudinally 80 of the member 6. These walls serve to reinforce or strengthen the downwardly projecting socket 9, and prevent the same from being broken off through a lateral movement or twist. The leather or rubber wearing surface 17, is attached to the heel by 85 means of nails 18, which are driven through the member 17, and into the member 14, the member 14 being preferably constructed of wood or leather.

While I have illustrated and described the preferred form of construction for carrying my invention into effect, this is capable of variation and modification without departing from the spirit of the invention. I, 100 therefore, do not wish to be limited to the precise details of the construction set forth, but desire to avail myself of such variations and modifications as come within the scope of the appended claims.

Having described my invention, what I

2.
claim as new and desire to secure by Letters Patent, is:

1. A heel comprising a hollow shell flared at its upper and lower extremities, an upper securing member adapted to lie within the upper end of the shell and provided with a plurality of laterally extending webs adapted to contact the interior of said shell, and a lower securing member within the lower end of the shell, said upper securing member adapted separately to be secured to the rear of a shoe, and means for drawing said two securing members together to position and hold said heel, and a wearing piece adapted to be detachably secured to said lower securing member.
2. A heel comprising a hollow shell flared at its upper and lower extremities, an upper securing member adapted to lie within the

upper end of the shell and provided with 20 a plurality of laterally extending vertically disposed webs adapted to contact the interior of said shell, and a lower securing member within the lower end of the shell, 25 said upper securing member adapted separately to be secured to the rear of a shoe, and means for drawing said two securing members together to position and hold said heel, and a wearing piece adapted to be detachably secured to said lower securing 30 member.

In testimony whereof I have signed my name to this specification in the presence of two subscribing witnesses:

WILLIAM NOLL.

Witnesses:

JOSHUA R. H. POTTS,
LAURA J. ERICKSON.
